COLLAPSIBLE CARDBOARD STRUCTURE

John V. Horr, North Tarrytown, N. Y., assignor to
Einson-Freeman Co., Inc., Long Island City,
N. Y., a corporation of Delaware

Application September 12, 1942, Serial No. 458,131

2 Claims. (Cl. 312—140.2)

My present invention relates generally to collapsible cardboard structures.

It is a general object of my invention to provide a structure which is adapted to be used as a serving bar, i. e., a device which may be caused to assume an upright position on the floor and provided with a horizontal supporting surface or bar top upon which bottles, glasses, and other paraphernalia may be rested to facilitate the serving of drinks or the like. The present structure is staunch and rugged in construction, and may be used on repeated occasions.

A more particular object of my invention is to provide a device which may be inexpensively manufactured of cardboard or its equivalent, thereby making it possible to sell the item at a low price or to award it as a premium for advertising or similar purposes.

A further object of my invention is to provide a structure which may be readily adjusted from a substantially compact collapsed condition into a rigidified sturdy set-up condition, and vice versa. This permits the structure, when collapsed, to be efficiently stored or shipped in a minimum amount of space.

The present improved structure consists essentially of front and back sections which are hingedly connected so that they may be collapsed together into superposed collapsed condition, or readily adjusted into separated relationship to form an upright tubular body adapted to rest firmly on the floor. Associated with this body structure is a member which is so shaped that it may be wedged into an operative position spanning the gap at the top of the tubular body, thereby forming a bar top or serving surface. These elements are so constructed and arranged, with respect to one another, and with respect to certain cooperating bracing elements, that the procedures involved in collapsing the device or adjusting it in set-up position are extremely simple and may be carried out even by unskilled persons.

In the preferred embodiment of my invention, the member which serves as the bar top is permanently hinged to at least one of the front and back sections so that it may be swung from an inoperative substantially vertical position to an operative substantially horizontal position. Preferably this bar top is hingedly connected to the back section of the structure, near the top.

The preferred embodiment of the invention also provides the front section with a scoring

which allows this section to bulge forwardly at the sides to form convex side portions on the front wall of the device when the structure is set up; and the bar top member is provided with a free edge which conforms to this convexity so that the various parts may be mutually braced in a simple yet efficient manner. The structure is preferably provided with a second bracing member, similar to the bar top member, but hinged to the back section at a lower region, thereby bracing the structure in a desirable manner at the lower part thereof.

A particular feature of my invention resides in the provision of a means which becomes automatically operative, when the structure is set up, to adjust the front and back sections into separated set-up relationship. This is preferably accomplished by a toggle link associated in a special manner with the bar top member. A similar toggle link may be used to advantage in association with the lower bracing member.

A further feature of my invention resides in the provision of at least one transverse brace which lies beneath and affords a strong support for the horizontal bar top when the structure is set up. A similar transverse brace is preferably provided beneath the lower bracing member, and the transverse brace at the lower portion of the structure is of further utility in strengthening and rigidifying the structure at the floor level.

I achieve the foregoing general objects, and such other objects as may hereinafter appear or be pointed out, in the manner illustratively exemplified in the accompanying drawing, in which—

Figure 1 is a perspective view of a structure constructed in accordance with the present invention, shown in set-up condition;

Figure 2 is a cross-sectional view taken substantially along the line 2—2 of Figure 1;

Figure 3 is a view similar to Figure 2 showing the parts in partially collapsed relationships;

Figure 4 is a plan view of the structure, in set-up condition, the bar top being partly broken away;

Figure 5 is a cross-sectional view taken substantially along the line 5—5 of Figure 1;

Figure 6 is a perspective view of one of the bracing and toggle elements, shown by itself; and

Figure 7 is a rear elevational view of the device shown in Figure 1.

The body portion of the structure is composed

of a substantially rectangular rear panel 10, and a wider substantially rectangular element 11 whose end portions 12 are secured, by adhesive means or otherwise, to the opposite margins of the panel 10. Vertical score lines 13 are provided in the element 11 at the opposite sides of the structure. These score lines are so positioned that the lineal distance between them, measured along the element 11, is substantially equal to the lineal distance between them, measured around the rear of the device. These score lines 13 may therefore be said to divide the structure into front and back sections hingedly connected at the sides. By the term "front section" it will be understood that reference is made to that portion of the element 11 which lies between the score lines 13; and by the term "back section," it will be understood that reference is made, as a unit, to the rear panel 10 and to those portions of the element 11 which lie rearwardly of the score lines 13.

Because of the fact that the width of the front section, when laid flat, is thus substantially equal to the width of the back section, when laid flat, it follows that the front and back sections may be collapsed together into substantially superposed relationship. This is the relationship which they assume when the structure as a whole is collapsed. When it is set up, the front and back sections assume the separated relationship shown in Figures 1, 2, 4 and 5, thereby forming an upright tubular body.

Adjacent to the score lines 13, the front section is preferably provided with a series of closely spaced vertical scorings which allow the front section to bulge forwardly in the convex manner shown in the drawing when the device is set up. This imparts an attractive appearance to the structure as a whole.

The element 14 adapted to serve as a bar top, is hinged to the back section near the upper edge of the latter. This is preferably accomplished by providing the member 14 with a rear extension 15 which is in hinged relation to the member 14 and which is secured, by adhesive means or otherwise, to the upper part of the rear panel 10. This allows the member 14 to be swung from an inoperative position substantially parallel to the rear panel 10 into an operative substantially horizontal position. The operative position is indicated in Figures 1, 2 and 4. In Figure 3, the member 14 is shown in an upwardly-adjusted position, but it will be understood that a complete collapse of the structure will bring the member 14 into substantially a vertical plane. The relationship of parts shown in Figure 3 (and shown also in dot-and-dash lines in Figure 5) indicates only a partial adjustment into completely collapsed condition.

The free edge of the member 14 is purposely caused to have a shape which conforms to the convexity of the front section of the tubular body; and the hinge line 16 is caused to lie slightly below the upper edge of the front section. Accordingly, when the member 14 is swung downwardly into an operative position, the free edge wedges itself into frictional engagement with the upper margin of the front section, and the parts are thus held in mutually braced relationship. Moreover, the upstanding edges of the front and back sections afford an attractive and useful guard rail to prevent articles from inadvertently sliding or falling from the bar top when the structure is used.

One of the features of my invention lies in the

fact that the member 14, during its adjustment into the operative position of Figure 2, automatically brings about a separation of the front and back sections. This is preferably accomplished by a toggle link 17. This link is hinged at its forward end to the front section of the tubular body, and at its rear end to the mid-portion of the member 14. This may be accomplished by providing a rear attachment flap 18 on the link 17, this flap being secured to the underside of the member 14, and by providing a similar forward attachment flap 19 on the link 17, the flap 19 being secured to the rear surface of the front section 11. The parts are so constructed that the rear hinge line 20 is exactly at the center of the member 14, while the hinge line 21 is in horizontal alignment with the hinge line 16. As a result, the link 17 and the rear portion of the member 14 serve as toggle braces, so that when the member 14 is swung downwardly, the front and rear sections of the body are mechanically forced apart until ultimately the member 14 lies flat, as shown in Figure 2, and the attachment flap 18 is in horizontal alignment with the toggle link 17.

In accordance with my invention, at least one transverse brace is provided to afford extra support for the bar top 14. Preferably, two spaced braces are provided, and they may advantageously be formed as integral parts of the attachment flap 19. One such brace consists of the strip 22 which is hinged at 23 to one side of the flap 19, and secured at its rear end, as at 24, to the rear panel 10. The strip is made collapsible by the provision of a score line 25 at its mid-portion. A similar bracing strip 26 is arranged at the opposite side of the attachment flap 19.

Each of the braces 22 and 26 is so positioned that when the structure is set up the upper edge of the bracing strip lies in a horizontal plane substantially coincident with the hinge lines 16 and 21, whereby the bar top 14 may rest firmly against these transverse braces when the structure is used.

To afford access to the underside of the member 14, so that this member may be pushed upwardly when a collapse of the structure is to be carried out, a hand hole 27 is provided in the rear panel 10 directly beneath the hinge line 16.

The structure may be efficiently reinforced in the lower region with an assembly of parts similar to those just described. Thus, the member 14 is in one sense a bracing member which spans the gap at the top of the tubular body and which assumes a reinforcing wedged position between the front and back sections when the structure is set up. A similar bracing member 28 is provided in the lower part of the structure, this member being hinged at 29 to the rear panel 10, and being adapted to swing from a substantially vertical position into the operative substantially horizontal position, shown in Figure 2. The member 28 may, if desired, form an integral part of the rear panel 10 as indicated in the present drawing. The member 28 has a free edge which conforms to the convexity of the front section, and is adapted to assume the wedged bracing position shown in Figure 2 when the structure is set up. Preferably, the member 28 is associated with a toggle link 30 and with transverse collapsible braces 31 and 32, these various elements being associated with one another and functioning in substantially the same manner as hereinbefore described in connection with the bar top member 14. It should be noted, however, that

the braces 31 and 32 extend all the way to the floor level, and that these braces thereby afford not only a bracing support for the member 28 but a reinforcement of the foundation of the structure at the floor level.

In order to make it easy to adjust the member 28 upwardly, when a collapse of the structure is to be carried out, the member 28 is preferably provided with a hand hole 33.

It will thus be seen that I have provided a structure of relatively simple character, requiring for its manufacture nothing more than cardboard or equivalent sheet material, and that the structure may be readily adjusted between a substantially flat collapsed condition and a rigidified operative condition. In setting the device up it is merely necessary for the user to press the members 14 and 28 forwardly until they assume the positions of Figure 2; and in order to restore the parts to a collapsed relationship, it is merely necessary to insert the hand through the hole 21 and impart an upward movement to the member 14, and to grasp the member 28 with the aid of the hole 33 and to pull the member 28 upwardly in a similar manner. Then, by merely pressing the front and back sections of the body together, the entire structure readily collapses into a substantially flat condition.

In general, it will be understood that the details herein described and illustrated for the purpose of explaining the nature of the invention may be modified by those skilled in the art without departing from the spirit and scope of the invention as expressed in the appended claims. It is therefore intended that these details be considered as illustrative and not in a limiting sense.

Having thus described my invention and illustrated its use, what I claim as new and desire to secure by Letters Patent is:

1. A collapsible cardboard structure adapted to be used as a serving bar, comprising upright

5 front and back sections hingedly connected at the sides to allow them to be collapsed together or to be separated to define a tubular body, a bar top member hinged to the upper part of the back section and adapted to be swung from an inoperative substantially vertical position into an operative substantially horizontal position spanning the gap at the top of said body when the structure is set up, and means controlled by said member 10 as it is swung into operative position for adjusting the front and back sections into separated set-up relationship, said means comprising a toggle link hinged at its forward end to the upper part of the front section and hinged at its rear end to the midportion of said bar top member.

15 2. A collapsible cardboard structure adapted to be used as a serving bar, comprising upright front and back sections hingedly connected at the sides to allow them to be collapsed together or to be separated to define a tubular body, a bar top member hinged to the upper part of the back section and adapted to be swung from an inoperative substantially vertical position into an operative substantially horizontal position spanning the gap at the top of said body when the structure is set up, means controlled by said member as it is swung into operative position for adjusting the front and back sections into separated set-up relationship, said means comprising a toggle link hinged at its forward end to the upper part of the front section and at its rear end to the midportion of said bar top member, and at least one transverse brace extending between the front and back sections and adapted to afford support for the bar top member when the latter is swung into operative position, said brace comprising a collapsible strip hingedly connected at its ends to the front and back sections, said brace and toggle link being portions of a single cardboard piece.

JOHN V. HORN.
